UNITED STATES PATENT OFFICE.

EDWARD YOUNG, OF PONY LAKE, NEBRASKA.

STOKER.

1,172,657.

Specification of Letters Patent. Patented Feb. 22, 1916.

Continuation of application Serial No. 847,292, filed June 25, 1914. This application filed April 12, 1915.
Serial No. 20,837.

To all whom it may concern:

Be it known that I, EDWARD YOUNG, a citizen of the United States, residing at Pony Lake, in the county of Rock and State 5 of Nebraska, have invented certain new and useful Improvements in Stokers, of which the following is a specification.

This invention relates to stokers for locomotives of the type illustrated in an application filed by me October 25, 1913, Serial 10 No. 797,226, and in which a rotary ejector operates within a casing provided at its open front end with a door and gates or deflectors which are adjusted to various positions 15 so as to control the deposit of fuel in the fire box.

The object of the present invention is to provide means whereby the door and deflectors will be automatically operated so as 20 to vary the point of deposit of the fuel upon the fire to the end that the entire surface of the fire may be supplied with fuel continuously.

In the accompanying drawings, which 25 fully illustrate my present improvements: Figure 1 is a plan view of a stoker showing one form of the present invention; Fig. 2 is a side elevation of the same; Fig. 3 is a transverse vertical section on the line 3—3 30 of Fig. 1; Fig. 4 is a detail elevation of a part of the gearing; Fig. 5 is a detail of another portion of the gearing; Fig. 6 is a plan view of a modification; Fig. 7 is a longitudinal section of the same on the line 35 7—7 of Fig. 6; and Fig. 8 is a detail view of the reversing trigger.

The stoker embodies a casing 1 having an 40 arcuate rear end, indicated at 2, and provided near said end with an opening or hopper 3 through which fuel may be passed into the casing. Said casing is located in the cab of a locomotive with the open front end thereof arranged within the opening of the fire box. The sides of the casing are straight 45 and parallel for the greater portion of their length, as shown at 4, and the top and bottom plates extend forwardly beyond the sides and are provided with lateral extensions 5 between which are mounted vertical deflectors 6 which are parallel at all 50 times and are adapted to form extensions of the sides or assume positions lateral thereto.

A door 7 is hinged at its upper edge to 55 the top wall of the casing at the front end

of the same and is adapted to swing in a vertical plane so as to entirely uncover the open front end of the casing or nearly cover the same in the operation of the device. When this door is in the position illustrated, the fuel ejected from the casing may 30 pass to the back of the fire box, and when the door is lowered the fuel will be deflected to points nearer the front of the fire box. When the deflectors 6 are in the position 65 shown in Fig. 1, the fuel may pass from the casing along the longitudinal line of the same, but as the deflectors are shifted, the fuel will be directed toward either side of 70 the fire box.

An ejector shaft 8 is mounted in the top and bottom plates of the casing and extends below the casing where it is connected to rotating and reversing mechanism, indicated generally at 9. This operating 75 mechanism may be of any desired construction and arrangement, and preferably comprises steam cylinders 10 which contain pistons operating through suitable mechanism upon the shaft 8, and the said mechanism 80 embodies movable elements controlled by a shifting lever 11 whereby the direction of rotation of the shaft 8 may be controlled.

The ejector comprises a series of blades 12 disposed radially to the shaft 8 and fast 85 to said shaft and adapted to sweep past the opening or hopper 3 so as to act directly upon the fuel passing through said opening and force the same from the casing. The ejector is provided with a bottom plate 90 13 which fits closely around the shaft 8 to prevent the entrance of dust and dirt to the bearing of said shaft and thereby prevent the clogging of the same and consequent wear thereon.

My invention has special reference to the mechanism for operating the deflectors 6 and the door 7. The ejector is equipped with a pinion 41 upon its upper end, which meshes with the straight face 48 of a double gear 46 which is carried by a lever 52, said lever being fulcrumed on the casing eccentrically to the gear whereby movement of the lever will carry the gear into or out of mesh with the pinion 41. To facilitate 100 this movement, the rear end of the lever is provided with any convenient form of handle, as indicated at 53. The beveled face 47 of the double gear meshes with a beveled pinion 49 to which is pivoted the rear end 105 110

of a pitman 50 having its front end pivoted to an arm 51 rising from the door. The pinion 49 is one-half the size or one-half the diameter of the gear wheel 46 so that it will make two complete revolutions while the wheel 46 is making one revolution, and the door is thus raised and then again lowered while the deflectors are being moved once from side to side. The lever 52 has a lateral branch from which rises an upturned arm 54 providing a bearing for the hub or axle of the pinion 49, as will be readily understood on reference to Fig. 3.

In the illustrated arrangement, the pitman 50 is not pivoted permanently to the pinion 49 but is constructed with a notch 55 adapted to engage over a wrist pin on the side face of the pinion. The pitman may thus be readily lifted out of engagement with the pinion, if it should be advisable to hold the door against movement at any time, and to retain it in a set position, I provide a series of recesses or notches 56 in the lower edge of the pitman which may be engaged over some convenient projection in the locomotive cab.

The deflectors 6 are connected by a link 42 to which is pivotally connected the front end of a lever 43, said lever being fulcrumed on the casing and connected at its rear end to a transverse rack bar 44 meshing with a pinion 45 which is fast to and concentric with the gear 46. As the ejector shaft rotates, the pinion 41 will impart motion to the gear 46 so that the pinions 45 and 49 will be rotated. Through the pitman 50, the pinion 49 will continuously raise and lower the door 7 and the pinion 45 acting upon the rack 44 will swing the lever 43 about its fulcrum so that the deflectors will be turned to one side, as will be readily understood. The several parts should be so proportioned that the door will be raised and lowered while the deflectors are moving from one to the other extreme position. It will also be noted that by shifting the gear 46 out of mesh with the pinion 41, the door and the deflectors may be held stationary while the ejector continues to operate and deliver fuel at a particular point of the bed of fire.

The actuating mechanism is shown somewhat diagrammatically and comprises alternately reciprocating rack bars 57, meshing with the pinions 58 on the ejector shaft. The pinions are provided with oppositely disposed pawls 59 on their opposite faces arranged to engage ratchet wheels 60 which are slidable on the ejector shaft but constrained to rotate therewith. It will be readily understood that the rack bars are driven directly by the pistons in the cylinders 10, the movement of which is reversed automatically by the action of valves in the steam chests on the sides of said cylinders.

It will also be understood that, as the rack bars work alternately, a continuous rotation in one direction will be imparted to the shaft. To reverse the direction of rotation, I provide means whereby the shifting lever 11 will be automatically vibrated as the deflectors reach the limit of their movement. A reversing bar 61 is slidably mounted on the casing and carries upstanding pins or lugs 62 disposed at opposite sides of the lever 43. A connecting lever 63 is fulcrumed on the side of the casing with its upper end connected to the end of the reversing bar and its lower end connected by an angle lever 64 with the shifting lever 11. The inner end of the shifting lever carries a yoke 65 which engages the hubs of the ratchet wheels 60. When the lever 43 reaches the limit of its movement, it strikes one of the pins 62 and thereby slides the reversing bar toward one side of the casing, the motion being transmitted through the connected parts to shift the ratchet wheels so that the formerly inactive ratchet wheel becomes active and the active wheel becomes inactive, the direction of rotation of the shaft being consequently reversed.

In the arrangement shown in Figs. 6, 7 and 8, the ejector shaft 8 is equipped with a pinion 14 at its upper end above the casing, and this pinion is adapted to mesh with a gear wheel 15 which is carried by a lever 16 fulcrumed upon the casing at a point in advance of the hub or axis of the gear wheel, and equipped at its rear end with any convenient form of handle 17 whereby it may be swung upon its pivot so as to move the gear wheel into or out of mesh with the pinion 14, as will be readily understood. The gear wheel 15 is adapted to mesh alternately with rack bars 18 and 19 which are connected at their front ends by a bar 20 to which is pivoted the rear end of a link 21 having its front end pivoted to an arm 22 extending upwardly from the door 7. It will be readily understood that, if the gear wheel be in engagement with the upper rack bar 18, as shown in Fig. 6, the door will be moved in one direction, and if the rack bars be shifted so as to bring the lower rack 19 into engagement with the gear wheel, the door will be shifted in the opposite direction, although the direction of movement of the gear wheel is not changed. A second gear wheel 23 is arranged above the gear wheel 15 concentric therewith, and this gear wheel 23 engages a transversely disposed rack bar 24 to which is pivoted the rear end of a lever 25 which has its front end pivoted to a link 26 forming a connection between the deflectors 6, as will be readily understood. This lever 25 is fulcrumed to and supported by a bracket 27 which is secured upon the top of the casing and projects over the bar 20 to provide clearance between the

lever 25 and the said bar and the rack bar 19. A reversing bar 28 extends between the front ends of the rack bars 18 and 19, and this reversing bar is formed with a longitudinal slot which receives a trigger 29 fulcrumed at its lower end to a bracket 30 secured upon the top of the casing and having its upper end projecting above the reversing bar of the lever 25.

10 The shifting lever 11 is connected by a link 31 with an angle lever 32 suitably mounted upon the rear end of the casing, and one arm of this angle lever is pivoted to a lever 33 which is fulcrumed upon the 15 top of the casing, as indicated at 34, and has its front end extending over the gear wheels 15 and 23. One of the said gear wheels is provided with upstanding diametrically opposite pins, indicated at 35, which are adapted to alternately impinge against the front 20 free end of said lever 33 and thereby actuate the shifting lever 11 through the intermediate connections so as to reverse the driving mechanism.

25 It is thought the operation of the apparatus will be readily understood. In the position shown in Fig. 6, the parts are in the midway position or just beyond the midway position with the gear wheels 15 and 23 30 rotating in the direction of the arrow, and the door 7 is raised to a horizontal position or a position slightly above the horizontal, while the deflectors 6 are parallel and form practically extensions of the sides of the 35 casing. The lever 25 has shifted the reversing bar 28 through its engagement with the trigger 29 so that the rack bar 19 has been moved out of engagement with the gear wheel 15 and the rack bar 18 has been 40 brought into engagement with said gear. As the rotation of the gear wheels continues, the rack bar 18 will be moved toward the front of the casing and, consequently, a push will be exerted upon the arm 22 which will 45 swing the door downwardly. At the same time, the rack bar 24 will be moved toward the lower side of the figure and the lever 25 will be actuated so as to swing the deflectors to the side. When the limit of the movement has been reached, one of the pins 35 50 will impinge against the free end of the lever 33 and will thereby vibrate said lever so as to actuate the angle lever 32 and link 31 thereby operating the shifting lever so 55 as to reverse the rotation of the driving mechanism. The rotation of the ejector shaft 8 will consequently be reversed, and the deflectors will then be swung about their pivots to the opposite limit of their movement, while the door 7 will be raised and 60 then again lowered. When the direction of rotation is reversed through the engagement of the pin 35 and the lever 33, the gear wheels 15 and 23 will rotate in a direction 65 opposite to that indicated by the arrow in

Fig. 1, and the rack bar 18 will then be moved rearwardly, while the rack bar 24 will be moved toward the top of the figure. When the parts reach the midway position, the lever 25 will strike against the upstanding end of the trigger 29 and will swing the trigger about its pivot and thereby, through the engagement of the trigger and the reversing bar 28, shift said reversing bar and the rack bars connected therewith so that 70 the rack bar 18 will be shifted out of engagement with the gear wheel 15 and the rack bar 18 brought into engagement with said gear. The direction of movement of the rack bars 18 and 19 will, consequently, 75 be reversed, although the gear wheels will not be reversed until a half revolution is completed, at which time the previously inactive pin 35 will engage the free end of the lever 33 and oscillate the same so as to reverse the driving mechanism, as previously described. It will thus be seen that, at each 80 half revolution of the gear wheels, the deflectors will be moved from one to the other 85 extreme position so that the fuel will be directed first to one side of the fire box and then to the other side of the same, while the door 7 will be raised from its lowest position to its highest position and then return to its lowest position. A thorough distribution of 90 the fuel over the surface of the fire is thus 95 automatically accomplished.

Having thus described the invention, what is claimed as new is:—

1. The combination with a casing, of a driving shaft mounted vertically therein, a pinion on said shaft, a door to cover or uncover the front end of the casing, deflectors mounted upon the casing adjacent said door, a lever fulcrumed upon the casing, a gear wheel mounted on said lever to be carried thereby into and out of engagement with said pinion, and means actuated by said gear wheel to operate the door and said deflectors. 100

2. The combination of a casing, fuel ejecting means therein including a rotatable and reversible shaft, means for controlling the discharge from the casing, means for actuating said discharge controlling means including a gear wheel mounted on the casing, means on the casing to move said gear wheel into or out of engagement with the said rotatable and reversible shaft, means below the casing for rotating and reversing said shaft, 105 a lever mounted on the casing and operatively connected with said rotating and reversing means, and means driven by said gear wheel for actuating said lever. 115

3. The combination of a casing, a stoker shaft journaled in the casing, an ejector carried by said shaft within the casing, laterally movable deflectors mounted in the casing adjacent the front end thereof, a vertically movable door mounted on the front 120 125 130

end of the casing, a gear wheel mounted upon the casing, gearing between said wheel and the deflectors, gearing between said wheel and the door, and means for moving said gear wheel into and out of engagement with the stoker shaft.

4. The combination of a casing, a stoker shaft mounted therein, an ejector carried by said shaft within the casing, laterally movable deflectors mounted at the front end of the casing, a vertically movable door hinged upon the front end of the casing, means mounted on the casing and driven by the stoker shaft whereby to shift the deflectors from side to side and simultaneously raise and then again lower the said door, and means mounted on the casing and actuated by the shifting of the deflectors to reverse the direction of rotation of the ejector shaft.

5. The combination of a casing, a shaft mounted therein, laterally swinging deflectors at the front end of the casing, a vertically swinging door mounted upon the front end of the casing, means driven by the stoker shaft for actuating said door, and means driven by the stoker shaft for actuating the deflectors comprising a vibratory lever, a reversing bar slidably mounted on the casing and arranged to be actuated by the said lever, and means controlled by said reversing bar to reverse the direction of rotation of the said shaft.

6. The combination of a casing, a stoker

shaft therein, means for rotating said shaft, means for periodically reversing the direction of rotation of said shaft, deflectors mounted at the front end of the casing and adapted to swing laterally, a door mounted at the front end of the casing and adapted to swing vertically, a gear wheel arranged to be driven by the stoker shaft, a rack bar actuated by said gear wheel, connections between said rack bar and the deflectors, a pinion rotated by the gear wheel, and a pitman connecting said pinion with the door.

7. The combination of a casing, a stoker shaft therein, means for rotating said shaft, means for periodically reversing the direction of rotation of said shaft, deflectors mounted at the front end of the casing and adapted to swing laterally, a door mounted at the front end of the casing and adapted to swing vertically, a gear wheel arranged to be driven by the stoker shaft, a rack bar actuated by said gear wheel, connections between said rack bar and the deflectors, a pinion rotated by the gear wheel, and a pitman connected with the door and provided with a notch adapted to engage over a wrist pin on said pinion.

In testimony whereof I affix my signature in presence of two witnesses.

EDWARD YOUNG. [L.S.]
